UNITED STATES PATENT OFFICE.

ERIC M. SMITH, ALBERT M. KEMP, AND JOSEPH E. FITZWATER, OF DENVER,
COLORADO.

AUTOMATIC STREET-INDICATOR FOR ELECTRIC RAILWAYS.

No. 849,276.

Specification of Letters Patent.

Patented April 2, 1907.

Application filed November 23, 1905, Serial No. 288,733.

To all whom it may concern:

Be it known that we, ERIC M. SMITH, ALBERT M. KEMP, and JOSEPH E. FITZWATER, citizens of the United States, residing at Denver, in the county of Denver and State of Colorado, have invented a new and useful Automatic Street-Indicator for Electric Railways, of which the following is a specification.

- 10 Our invention comprises a rotating cylinder carrying hinged skeleton leaves to hold printed cardboard signs and actuated by a positive ratchet mechanism having an automatic reversing device.
- 15 The object of this invention is to provide means whereby a passenger may at any time by a glance at the indicator learn the name of the next street, and thus be prevented from passing his destination. We attain this object by means of the mechanism illustrated in the accompanying drawings, in which—

20 Figure 1 is a cross-section of the machine on line 2 2 of Fig. 3. Fig. 2 is a full-sized end view of one of the hinged card-carrying skeleton leaves. Fig. 3 is a vertical longitudinal section of the machine on line 1 1 of Fig. 1, parts being removed for the sake of clearness of illustration. Fig. 4 is a section on line 3 3 of Fig. 3 looking in the direction opposite that shown in Fig. 1 and with the card-carrying leaves removed for clearness. Fig. 5 is a view of the trolley attachment looking along the trolley-wire; Fig. 6, a side view of the same, and Fig. 7 a detail of the circuit-closer hereinafter described.

25 Similar letters refer to similar parts throughout the several views.

The frame of the rotatable card-carrying mechanism comprises a pair of disks E I, having hubs F and J with axial apertures U, spaced apart by and threaded into the tube H. The axis of this frame is a shaft (omitted in the figures for the sake of clearness of illustration) resting in bearings Z, attached to 30 the main frame of the indicator.

The disks E I are each provided near their peripheries with a series of equally-spaced holes p, adapted to receive the ends of the rods C, which carry the skeleton leaves A, in 35 which are inserted cards bearing the desired street designations. These leaves are stamped from suitable sheet metal, as steel, and each folded or pressed round its pivot-rod C, so as to rotate therewith. Near that

end of each rod C which is designed to pass 55 through the disk E is firmly attached a fork B, and these forks may be longitudinally spaced on the rods in sets of three or more, as shown at the left of Fig. 3, so as not to interfere when oscillated, as shown at the junction of the position-planes 2 3, Fig. 1.

As the leaf-carrying frame is given a step-by-step rotation in either direction by means hereinafter described, the forks B are adapted to engage a stationary pin D to give to the 65 name-cards the successive positions 1 2 3 4, Fig. 1, or vice versa, according to the direction of rotation. The pin D has a head adapted to be adjustably held by a screw G in a slot in the lug W in the main frame. 70

The ratchet-wheel K is fixedly attached to the disk I by the hollow screw-hub J and is adapted to be given a step-by-step movement in either direction by the reversible pawl N, mounted on the oscillating lever M, 75 which is pivoted on the threaded sleeve or pivot R. The pawl N is attached to lever M by a screw-pivot O and has in its broadened upper end two conical recesses T, each adapted to receive the coned end of a pin P, 80 which passes through a sleeve n near the upper end of the lever M and is yieldingly held in one or the other of the recesses T by a spring n'. By this construction the pawl is held in driving contact with the ratchet-wheel K, but may be automatically reversed by means which will now be described.

The threaded sleeve or pivot R secures the forked or three-armed lever L coaxially to the lever M, but in such manner that they 90 may oscillate independently about R. Each of the three ends of L is bent at right angles to its arm, the two upper ends for the purpose of contacting with the beveled ends of pawl N to reverse it at the proper time and the 95 lower end to contact with pin m, inserted in one of a series of holes r, provided in the disk I near its periphery. One such pin, as shown in Fig. 4, may be permanently secured in the disk at a point corresponding to the card or 100 frame which marks the beginning of a route, while a second pin may be removably inserted in any hole r that may be necessitated by the number of cross-streets on the route.

The actuating means for the lever M comprises a curved soft-iron core Q, secured to one side of its upper end and a tension-spring V, secured to the opposite side and having

its other end attached to a lug on the main frame. A curved solenoid X is suitably positioned to attract the core Q when a current passes through the coil.

5 A spring-dog Y holds the wheel K stationary during the backward or non-driving swing of lever M, and suitably-positioned stop-pins may be provided on each side of the lever M to limit its throw.

10 The means for exciting the solenoid are shown in Figs. 5, 6, and 7. The trolley-wheel *a* is mounted in a fork or casing *b*, attached to the trolley-pole *c* in the usual manner. A member *f*, of conducting material, preferably copper, is mounted in a boss *g* by means of washer *h* and bolts *i*, the parts *f* and *g* being suitably insulated from each other. A wire is inserted in hole *l* in the inner end of *f*, is clamped therein by screw *k*, 20 and passes thence down the trolley-pole, being suitably insulated therefrom, and thence to one terminal of solenoid X, the other terminal of the solenoid being connected to the rails or other return in any desired or well-known way.

25 On the trolley-wire *j* at the far side of each street-crossing is clamped a contact *e*, of conducting material, preferably copper, by means of the member *d* and fastenings *q*. The 30 above-described means are preferred for use with overhead systems; but it will be readily understood that other means for exciting the solenoid at predetermined points may be substituted therefor either in overhead or underground systems.

35 The operation of the indicator is as follows: As the car approaches a street-crossing the name of the intersecting street will be visible to the passengers through a glazed opening 40 opposite the card shown at 3, Fig. 1. As soon as the intersecting street has been crossed member *f* strikes one of the contacts *e*, exciting solenoid X, attracting Q, and swinging lever M to move wheel K one notch, 45 or to retract the lever, so that it will be in position to actuate K by the pull of spring V as soon as the circuit through X is broken, according to the position of the pawl N, as will be readily understood. This swings an adjacent indicating-leaf to the position 3, where it remains to the end of the block. This operation is repeated until the end of the line is reached, when, having been properly adjusted for the route, the pin *m* engages the reversing-lever L and reverses the pawl N by pressing the inturned end of one of the upper arms of the lever L against the beveled surface of the pawl N, thus depressing this end of the pawl, rotating it about the pin *o* to disengage the spring-pin P from one of the conical recesses T and seat it in the other of said recesses. The other upwardly-projecting arm of the lever L is by this movement swung away from the opposite end of the 60 pawl N to permit that end to rise from the

periphery of the ratchet-wheel K. The card-carrying cylinder is then rotated in the opposite direction, and the names of the streets appear in reverse order until the other end of the line is reached. After the pins *m* have been adjusted for a specified route the operation of the indicator is entirely automatic.

The advantages of our invention are as follows: First, by the use of our skeleton leaves the indicator may be used on any line in the 75 city by simply changing the signs to correspond with the cross-streets in this line, or by loosening two thumb-screws the entire instrument, which is easily carried, can be lifted from its brackets and transferred to another car; second, after being set to the proper street at the beginning of the run the operation is entirely automatic until the run is changed; third, the circuit-closer may be placed anywhere along the wire regardless of 85 the hangers for the wire, and any number of them may be placed in a small space; fourth, the motion is positive in each direction, and only as many leaves need be used as there are streets on the line; fifth, it is simple in construction, the number of parts being few 90 considering the work done, is easily adjusted, and cheap in cost.

Aside from the indicator itself an entire system can be prepared for its user with a 95 very small amount of labor and expense.

Many changes may be made in our indicator by the skilled mechanic without departing from our invention, since

What we claim is—

100 1. In a street-indicator, a rotatable cylinder, a plurality of signs pivotally mounted thereon, means for giving said cylinder a step-by-step movement to display said signs successively and automatic means for reversing the direction of the cylinder movement.

105 2. In a street-indicator, a rotatable cylinder, a plurality of signs pivoted to said cylinder, means for advancing said signs successively to display position and means for reversing the direction of rotation of said cylinder to move said signs to display position in reverse order.

110 3. In a street-indicator, a rotatable member, a plurality of signs pivotally mounted thereon, a ratchet-wheel secured coaxially with said member, a fork mounted on the pivot of each sign, a stationary member adapted to engage said forks and display 115 signs successively in either direction of movement of said member, an integral, double-ended pawl for driving said ratchet-wheel in either direction, and means for automatically reversing the driving position of 120 said pawl.

125 4. In a street-indicator, a reversible rotatable cylinder, a series of signs pivoted near the periphery of said cylinder, forks pivoted coaxially with each of said signs, a 130

pin arranged to engage said forks successively to move said signs to display position in either direction of rotation of said cylinder, and a single, reversible driving means for driving said cylinder in either direction.

5. In a street-indicator, a rotatable cylinder, a plurality of signs pivotally mounted thereon, a ratchet-wheel mounted coaxially with said cylinder, an integral, double-ended pawl for driving said wheel and cylinder in either direction and means for automatically reversing the driving position of said pawl at a predetermined point.

6. In a street-indicator, a rotatable cylinder, a plurality of signs pivoted thereto, reversible ratchet-and-pawl mechanism for intermittently rotating said cylinder, electrically-operated means for oscillating said pawl mechanism, means for closing the circuit of 20 said electrically-operated means at predetermined points, and means for automatically reversing said pawl mechanism.

7. In a street-indicator, a movable sign-carrying member and actuating means therefor, said means comprising an oscillating lever, a pawl carried thereby a spring adapted to drive said lever and sign-carrying member in one direction, a solenoid adapted to drive said lever and sign-carrying member in the 30 opposite direction, means for passing a current through the solenoid-winding at predetermined intervals, and automatic means for reversing the pawl carried by said lever.

8. In a street-indicator a rotatable sign-carrying member and actuating means therefor, said means comprising a pawl-lever, an integral, double-ended pawl thereon, a solenoid-core mounted on an extension of said lever, a circuit comprising the winding of 40 said solenoid and extending from a feed-main to a return, contacts removably mounted on the feed-main and arranged to close the circuit through said solenoid, a spring connected to the lever and adapted to 45 drive said lever and rotate the sign-carrying member when the solenoid-circuit is broken

and automatic means for reversing the driving position of said pawl.

9. In a street-indicator, a movable sign-carrying member and actuating means therefor, said means comprising a reversible ratchet-wheel, a lever carrying an integral, double-ended pawl arranged to engage said wheel, a spring-dog for holding said wheel during the non-driving movement of said pawl, means for oscillating said lever, and automatic means for reversing the driving position of said pawl.

10. In a street-indicator, a movable sign-carrying member and actuating means therefor, said means comprising a reversible ratchet-wheel, a lever carrying an integral, double-ended pawl arranged to engage said wheel, a spring-dog for holding said wheel during the non-driving movement of said pawl, and automatic means for reversing the driving position of said pawl at predetermined intervals.

11. A street-indicator comprising a rotatable cylinder, a plurality of pivoted skeleton leaves mounted adjacent to the periphery of said cylinder, a fork pivoted coaxially with each of said leaves, an adjustably-mounted stationary pin positioned to engage said forks successively, a ratchet-wheel 75 mounted coaxially with said cylinder, an oscillating lever having an integral, double-ended pawl mounted in operative relation with said wheel, a three-armed lever having two of its arms positioned to reverse the driving position of said pawl and a plurality of pins removably mounted in said cylinder and arranged to engage the third arm of the three-armed lever to actuate said pawl at predetermined positions of said cylinder.
